UNITED STATES PATENT OFFICE.

GEORGE H. HILL, OF GLENRIDGE, NEW JERSEY, ASSIGNOR TO SPRAGUE ELECTRIC COMPANY, OF NEW YORK, N. Y., A CORPORATION OF NEW JERSEY.

METHOD OF CONSTRUCTING ELECTRIC SWITCHES.

SPECIFICATION forming part of Letters Patent No. 712,535, dated November 4, 1902.

Original application filed August 10, 1901, Serial No. 71,640. Divided and this application filed January 24, 1902. Serial No. 91,067. (No model.)

To all whom it may concern:

Be it known that I, GEORGE H. HILL, a citizen of the United States of America, and a resident of Glenridge, in the county of Essex and State of New Jersey, have invented certain new and useful Improvements in Methods of Constructing Electric Switches, of which the following is a specification.

This invention relates to a method of constructing electric switches, particularly switches of the cylindrical type, in which spider-castings on the shaft are insulated therefrom by an insulating compound, as shown in my copending application, filed August 10, 1901, Serial No. 71,640, and of which this is a division. Heretofore the segments or castings have been painted, after they have been assembled on the shaft, in such a way that whenever dust, oil, and dirt accumulated on

the surface of the compound between the castings a leak of current occurred between them. In a short time a heavy arc would form, with the consequent burning out of the switch. Also as the coat of paint furnishes a film or skin over dissimilar substances—namely, the castings and the compound—it is apt to crack, and thus give opportunity for an initial leak.

The object of the present invention is to provide a method of constructing electric switches by which the insulation is made more effective and these defects avoided; and the invention therefore consists of certain novel features to be hereinafter described in detail and then pointed out in the claims.

In the accompanying drawings, Figure 1 is a side elevation of so much of a switch constructed in accordance with the present invention as suffices to illustrate the same. Fig. 2 is a section on line 2 of Fig. 1, the brushes being omitted; and Fig. 3 is a section on line 3 of Fig. 1.

The shaft or spindle A of the switch, here shown as of the cylinder type, is covered with an insulating compound B, so as to form a layer under and between the castings or segments C, the lugs C' of which carry the copper contacts D. The brushes are lettered D'.

The well-known way of applying the insulating compound and castings to the shaft is to string a number of rings of suitable insulating compound upon the shaft and then set and hold the castings thereupon, so that they will not change their relative position to each other. This having been done, the parts are subjected to heat, as by means of gas-jets, so as to soften up the rings of insulating compound and make them plastic. Other rings are forced on the shaft, so as to squeeze the softened and now plastic material up into the interstices between the castings, and the process is continued until all of the interstices are filled with the compound, when the structure is allowed to cool off, and the exposed surfaces of the insulation and the castings are then covered with a coat or coats of paint.

In the present invention the described method of assembling is also preferably used; but before assembling the castings C are enameled or japanned with some suitable insulating material E—such as porcelain, for instance. This enamel or japan is hard and baked on the castings, so that it will resist the subsequent heating at the time the insulating compound is applied to the shaft.

The enamel or japan also provides a hard insulating-skin on the castings which is not readily broken down, and thus prevents the initial leak between the castings, and consequently the disastrous arcing which follows. A coat of paint F may or may not be applied to the exposed surfaces of the insulation and castings, as heretofore, as shown in Figs. 2 and 3.

The painting of the castings after they have been assembled upon the shaft is not as advantageous as previous enameling or japanning, for the reasons that the paint cannot be hard-baked on account of the low-temperature limit of the insulating compound, and is therefore not as durable, and also that the paint is liable to crack.

What I claim as new, and desire to secure by Letters Patent, is—

In the herein-described method of con-

structing electric switches, the following steps, namely, first applying a skin or film of insulating material to the contact-support, and then applying, under the action of heat, 5 an insulating compound over the skin or film covered portion of the support, substantially as described.

Signed by me at New York, N. Y., this 22d day of January, 1902.

GEORGE H. HILL.
